CLAIM

The ornamental design for an all-purpose row-crop wheel tractor, as shown.

DESCRIPTION

FIG. 1 is a perspective view of an all-purpose row-crop-wheel tractor showing our new design;

FIG. 2 is a side elevational view taken from the right of FIG. 1;

FIG. 3 is a front elevational view thereof, the antenna is omitted for convenience of illustration;

FIG. 4 is a side elevational view taken from the left of FIG. 1;

FIG. 5 is a rear elevational view thereof; and

FIG. 6 is a top plan view thereof.
